Patented Nov. 14, 1916.

UNITED STATES PATENT OFFICE.

JAMES R. SHEFFIELD, OF CARTHAGE, NORTH CAROLINA.

MAIL-TRANSFERRING APPARATUS.

1,204,596.

Specification of Letters Patent. Patented Nov. 14, 1916.

Application filed August 3, 1914. Serial No. 854,764.

To all whom it may concern:

Be it known that I, JAMES R. SHEFFIELD, citizen of the United States, residing at Carthage, in the county of Moore and State 5 of North Carolina, have invented certain new and useful Improvements in Mail-Transferring Apparatus, of which the following is a specification.

My invention relates to devices for transferring mail.

The primary object of the invention is to provide an improved, simplified and efficient receiving means, so arranged relatively to co-acting delivery means as to positively 15 and safely transfer mail matter from a fast moving train to a stationary support or vice versa.

The above and additional objects are accomplished by such means as are illustrated 20 in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a perspective view of the transferring apparatus illustrating the application of the invention; Fig. 2 is an elevation, the car being shown in section, of the support means mounted on the car; Fig. 3 is a fragmentary side elevation of the delivery end of the stationary support; Fig. 4 is a fragmentary sectional view of the parts illustrated in Fig. 3; and Fig. 5 is a similar 40 view of the receiving end of the support means mounted on the car.

Referring now to the drawings by numerals, 1 designates an ordinary railway mail car, through the door of which, support means for the mail matter acted upon projects. In its preferred embodiment, the support means comprising the present invention consists of an arm 2 pivoted as at 3 to the door frame, said arm being braced 45 as at 4, the brace member being also pivoted in axial alinement with the pivot 3 above noted. Any suitable catch device such as indicated at 5 may be provided to lock the support or arm 2 in its extended or operative position.

Arm 2 at its outermost end is branched

to form an upper extension 6 and a lower extension 7, the former being cut away at a point adjacent its free end as indicated at 8 to form a seat within which is fitted and pivoted as at 9 the support or delivery member 10 forming a part of the car-carried transferring means. An extension 11 is formed integrally with that portion 6 of the support means adjacent or at each side of 65 the groove 8 within which the member 10 is pivoted, the respective extensions 11 serving as a means whereby the said member is supported in a substantially horizontal plane when swung to extend in either direction as 70 will hereinafter appear.

Extension 7 is provided with a groove 8 and projections 11 in substantially the same manner as the extension 6, an arm 12 or receiving member being pivoted in the groove 75 and supported in a substantially horizontal plane or parallel with the member 10, preferably at a point directly therebeneath. Each member 10 and 12 is provided with a transverse pin 13 to serve as a stop means 80 limiting inward movement of the mail bag when suspended therefrom.

A stationary support 14 is positioned at one side of the railway track in the usual manner, said support member 14 consisting 85 of an arm 15 pivoted as at 16 and terminating at its free end in extensions designated respectively 17 and 18. Extension 17 is bifurcated at its free end to receive an arm or receiving member 19, the said member being pivoted to the extension in such a manner as to be swung in the arc of a circle 160°, any suitable support means such as that indicated at 11 in the subject matter above referred to, being provided therefor. Member 90 19 may also be provided with a transverse pin as shown. Extension 18 is also bifurcated at its free end to receive a delivery member or arm 20, the latter being pivoted in such a manner as to be swung from one 100 to the other side of the said extension, the support means therefor when swung at either side consisting of a removable element 21 fitting the bifurcation and being held in place through the medium of bolts 22 105 extending therethrough as shown to advantage in Figs. 3 and 4.

When it is desired that mail matter be transferred from a moving train to the stationary support, the said mail matter is suspended from the arm 10, the mail bag having associated therewith a ring 23 which, by

reason of the weight of the mail bag is held in the path of arm 19 of the stationary support so that the latter, as the train passes the support, will cause the arm to engage the 5 ring and remove the mail matter from the said arm 10. A transfer of mail from the stationary support to the moving train is accomplished in much the same manner, the mail matter being suspended from arm 20 10 so that the ring is positioned in such relation to arm 12 as to be engaged thereby. When mail matter is suspended from both the arm 10 and the arm 20, the transfer of the mail matter onto the arm 19 and onto 15 the arm 12 is simultaneous.

From the foregoing, taken in connection with the accompanying drawings it is apparent that the arms 10, 19, 20 and 12 may be swung to extend in the direction opposite 20 to that shown so as to effect transfer should the train be moving in an opposite direction to that indicated by the arrow in Fig. 1; that the transferring device mounted on the car may be swung into an inoperative position 25 when not in use; and that the several arms are shaped in such a novel and peculiar manner as to facilitate transfer.

In reduction to practice, I have found that the form of my invention, illustrated in the 30 drawings and referred to in the above description, as the preferred embodiment, is the most efficient and practical; yet realizing that the conditions concurrent with the adoption of my device will necessarily vary, 35 I desire to emphasize the fact that various minor changes in details of construction, proportion and arrangement of parts may

be resorted to, when required, without sacrificing any of the advantages of my invention, as defined in the appended claims. 40

Having thus fully described my invention, what I claim as new and desire to secure by Letters Patent, is:—

1. A mail receiving device including a vertical support bifurcated at one end to receive between the extensions thus formed an arm, said arm being movable to extend laterally of the support from either side thereof, and a detachable supporting element mounted between said extensions to engage 50 with the under side of the arm whereby to support said arm in a substantially horizontal plane and against movement subsequent to adjustment.

2. A mail receiving device including a support bifurcated at one end, an arm pivoted between the extensions formed by said bifurcation, said arm being movable in a substantially vertical plane to extend laterally of the support from either side thereof, 60 and a detachable supporting element of a size to extend beyond the opposite longitudinal edges of the support, said supporting element being mounted between said extensions to engage with the under side of the 65 arm whereby to support said arm in a substantially horizontal plane and against movement subsequent to adjustment.

In testimony whereof I affix my signature in presence of two witnesses.

JAMES R. SHEFFIELD.
